ENVELOPE

Charles S. Watson, Glen Ridge, N. J., assignor to Berlin & Jones Company, Incorporated, New York, N. Y.

Application December 9, 1954, Serial No. 474,071

1 Claim. (Cl. 229—70)

This invention relates to envelopes suitable for mailing in connection with bank accounts and the like, and particularly to a special banking envelope.

The main object of my invention is to provide a banking envelope that facilitates depositing or withdrawing money from a live account in a bank by mail.

An important object of the invention is to have such an envelope provided with means for readily setting out how much is to be withdrawn and submitted to the sender of the envelope, and also fully identifying deposit checks and all features in connection with deposit or withdrawal of funds.

Another object of this invention is to have means connected to the envelope serving as a mail receipt for the bank that may be returned to the depositor and show amount deposited or withdrawn in the transaction.

A further object of the invention is to have the envelope provided with the mail deposit and/or withdrawal slip, order and mail receipt in the form of a flap extension on the mail flap and an additional end flap, with individual identifying indicia upon each to facilitate filling out by the sender and use by him and the bank.

It is also an object to have such flap extension and end flap separable from the main flap of the envelope, at will when the envelope is to be used and mailed.

An ancillary object is to provide a gummed strip upon the main flap of the envelope and the flap extension that is adapted to be separated therefrom for use and insertion into the envelope at mailing.

Other objects and advantages of my invention will appear in greater detail as the specification proceeds.

In order to facilitate ready comprehension of this invention for a proper appreciation of the salient features thereof, the invention is illustrated on the accompanying drawing forming part hereof, and in which:

Figure 1 is a front perspective view of the envelope embodying the invention in a practical form, being shown closed;

Figure 2 is a rear perspective view of the same closed envelope;

Figure 3 is a perspective view of the envelope during the first step of opening the same;

Figure 4 shows in another perspective view the envelope in the second fully open stage of the envelope exposing the features of the flap extension and end flap inner sides; and

Figure 5 is a plan view or layout of the initial pattern for making the envelope of the present invention.

In these various views, the same reference numerals indicate the same or like features throughout.

Banking envelopes are, of course known to a certain extent, but they are either complex in form or in use, and leave several gaps in information or opportunities for errors and wrong or defective entries, not to mention excessive or awkward numbers or sizes of flaps upon the envelope involved. Various expedients have, of course been tried, but as yet no really useful banking envelope

2

of simple yet effective character has come to dominate the market.

Upon considering this problem, it has occurred to me that an envelope for such purposes should be available that is simple to fill out and mail and free from any complications heretofore evident. As a result of such consideration, I have succeeded in producing a simple and substantially fool proof banking envelope that well appears to serve the objects already outlined, as will now be set forth in detail in the following.

Hence, in the practice of my invention, and referring also again to the drawing, a special envelope for the present purpose, generally indicated at 6 primarily includes a front address panel 7 for the address of the bank to which it is addressed at 8 and the sender's address 9. The rear or back panel 10 is integral with the front panel 7 at one end 11, while it is pasted upon a narrow end flap at the other end of the envelope at 12, and at the bottom, a low flap 13 connected to the front panel 20 is folded over the lower edge of the rear panel and pasted to the same. From the upper edge of the front panel extends an integral main flap 14 having a strip of paste or glue 15. I prefer to have the paste or glue strip 16 on the inside of end 17 of the rear panel, by 25 which the latter is attached to end flap 12.

Upon the main flap 14 is a flap extension 18 integral with it with a weakened line 19 between, while connected at one end is an end flap 20 integral with extension 18 and capable of being folded over the latter so 30 as to be co-extensive therewith as shown in Figure 3 or folded out free as shown in Figure 4. The end flap has another weakened line 21, allowing this end flap to be separated at will, even as line 19 allows extension 18 to be separated from main flap 14 when desired.

35 The mentioned flap extension upon its inner surface carries the heading "Mail Receipt" with places for credited and charged items with name and address of the party depositing or withdrawing funds. Upon the inner surface of end flap 20 is a heading "Mail Withdrawal Order" 40 with places for the date, bank book number and amount to be withdrawn from the account in the bank and for signature of withdrawer, as well as the name of the bank involved. On the outer side of the same end flap are placed heading "Mail Deposit," name of the bank and its address, and the remaining features of a deposit slip generally noted 22, the indicia upon its interior side being indicated at 23 (Figure 4), while upon the inner side of the flap extension 18, the indicia appear generally indicated at 24 as shown in Figure 4 also.

50 When it is desired to deposit money, checks and the like, they are recorded on the deposit side 22 of flap 20 and then the name is not only signed upon the same side but also printed by hand on the mail receipt side 24 of extension 18 and the latter torn off main flap 14 and the two members 18 and 20 placed with the checks, money, 55 money orders and the like in the envelope 6 and the main flap 14 pasted down upon rear panel 10 to close it. When the sender puts his name and address at 9 and a stamp on the envelope, it is ready to drop into the mail. If the sender intends to withdraw funds instead of depositing, he fills out the inner withdrawal order side 23 of end flap 20 and signs the same instead of the deposit side 22, and in that form places the flap extension 18 and flap 20 60 into the envelope before sealing. In either case, these two flap members are separated from flap 14 along line 19 and together as a folded unit placed in the envelope.

When the bank receives this envelope, the teller notes if deposit or withdrawal is desired and checks the mail receipt accordingly, separating it from flap 20 which he keeps and mails back the flap member 18 with the mail receipt 24 credited or charged, as the case may be. This 65 obviously facilitates operations at the bank and is so

simple an operation that the transaction is expeditious and can scarcely allow of any error occurring.

The envelope may be made of any useful quality of paper and be cut of any desired size, the pattern of Figure 5 determining the size, shape and location of the panels and flaps by their location on this pattern.

Manifestly, variations may be resorted to, and parts and features may be modified or used without others within the scope of the appended claim.

Having now fully described my invention, I claim:

A self-contained banking envelope, including a laterally elongated rectangular front address panel with short vertical ends, a laterally elongated rear panel integrally connected at one end thereof to one short vertical end of the front address panel and having the upper longitudinal edge thereof cut a short distance down below and parallel to the upper longitudinal edge of said front address panel with a glue strip upon the other outer end of said rear panel, a short end flap on the other short vertical end of said front address panel adapted to be secured to said glue strip on the rear panel, a short flap also integrally connected to the lower edge of the same front address panel, a relatively large main closure flap integrally connected to the upper edge of the latter front address panel and having a longitudinal glue strip located within the upper edge thereof for securing said main flap down upon said rear panel below the cut down upper edge of

the latter, an upwardly extending integral flap extension on the main flap having short vertical ends and a longitudinal weakened tear line upon the upper portion of said main flap allowing the upwardly extending flap extension to be torn off to serve as a mail receipt slip, and a laterally elongated end flap integrally connected to one short vertical end of said upwardly extending flap extension and having a vertical weakened tear line substantially aligned with the vertical short end of the front address panel to 10 which the rear panel is connected to allow independent removal of said laterally elongated end flap for the latter flap to serve as a deposit or withdrawal slip, the lower edge of said laterally elongated end flap being aligned with the weakened tear line on the main closure flap 15 when said elongated end flap is extended from the upwardly extending flap extension laterally, and the latter flap extension and said laterally elongated end flap being substantially equal in area and co-extensive when folded together one upon the other.
